UNITED STATES PATENT OFFICE.

FRANKLIN E. ABBOTT, OF BUFFALO, NEW YORK, ASSIGNOR TO LACKAWANNA STEEL COMPANY, OF LACKAWANNA, NEW YORK, A CORPORATION OF NEW YORK.

SPICE-BAR.

1,152,375.

Specification of Letters Patent. Patented Aug. 31, 1915.

Application filed March 8, 1915. Serial No. 12,831.

To all whom it may concern:

Be it known that I, FRANKLIN E. ABBOTT, a citizen of the United States, residing at Buffalo, in the county of Erie and 5 State of New York, have invented new and useful Improvements in Splice-Bars, of which the following is a specification.

My invention relates to improvements in splice-bars for rail joints of the shape now 10 in common use whereby danger of damage to said splice bars is overcome.

I use the term "splice-bar" to include fish-plates and angle-bars, to both of which forms my invention may be applied, but 15 have particularly shown my invention as applied to angle-bars. These angle-bars as now commonly made, are uniform throughout their entire length. The upper and lower bearing surfaces, when the angle-bars are in place, engage respectively with the under surface of the rail head and the upper surface of the rail flange, and fit snugly into what is called the "fishing" angle of the rail section. It results from this that 25 the uniform upper bearing surface of the splice-bar, coming in contact with the under surface of the rail head, extends from one rail to the other, and necessarily is in contact with the edges or corners on the under 30 surfaces of the rail ends. The effect of this contact when the tracks are in service is (1st) to cut or wear the splice-bar at its center, often starting a fracture and (2nd) to hammer and upset the metal of the splice-bar at the joint, and also to reduce its ductility, thus tending to weaken the splice-bar at the point of greatest stress when the top 35 of the bar is brought in tension, often resulting in fractures which have their beginning 40 at the top of the bar at or near the center. It will be understood that when the rail joint is in action, the splice-bar has to withstand alternating strains of compression and tension in both upper and lower surfaces. 45 The upsetting and wear of the metal at the center in the top of the bar tends to weaken it at the point of greatest stress when the top of the bar is brought in tension. This often results in fractures which have their beginning 50 at the top of the bar or near the center, through the metal which has been damaged by the rail ends.

To prevent damage to the metal at said upper portion of the splice-bar, I have designed an improvement in shape as shown 55

in accompanying drawings. This consists simply in making a depression in the top bearing surface of the splice-bar at the central part of its length thus producing and insuring a short clearance between the 60 splice-bar and extreme ends of the rail heads, to preserve the surface of metal in the depression in the same condition as when it is finished, and also to avoid upsetting and wearing it at that point. This 65 preserves the section and maintains the full strength of the bar at the center, where it is subjected to the greatest strains and to consequent frequent breaks.

My invention accordingly is embodied in 70 the improved form of bars hereinafter described and illustrated in the accompanying drawing wherein the reference characters of this description are applied to corresponding parts in the several views. 75

In the drawings Figure 1 is a view in side elevation of a rail joint employing my improved form of angle-bar. Fig. 2 is a central cross-sectional view thereof on lines 2—2 of Fig. 1. Fig. 3 is a partial inside elevation 80 of one of the bars. Fig. 4 is an end view of the bar of my invention. Fig. 5 is an end elevation of a fish-plate. Fig. 6 is a partial side elevation showing a modification.

In the figures R indicates the adjoining 85 sections of rail having their ends substantially in abutting relation with the usual small space left between them. The joining of the rail ends as here shown is accomplished by splice-bars B (angle-bars) arranged on opposite sides of the rail and clamped thereto by the usual securing bolts b—b, having threaded on their end the usual securing nuts n. 90

In accordance with my invention clearance is provided for between the under surface of the rail heads h' at their extreme ends and the splice-bar, and this is desirably effected by simply making a depression d 95 of suitable size centrally in the upper surface of the splice-bar, thereby preventing contact with the sharp corners on the under side of the rail heads. This depression in the bar is desirably formed as shown by rolling or pressing the metal when hot, but may be formed by shearing or otherwise as will be readily understood. I prefer however to modify the shape by rolling or pressing, for by that method there is no reduction 100 in the metal at any point, and the bar is 105 110

maintained of uniform strength from end to end. This depression may be one-eighth inch, more or less, in depth, and one inch, more or less, in length, but I do not desire to limit myself to any particular proportions. The clearance thus provided will prevent damage to the metal on top of the splice bars thereby keeping the surface of the metal in the depression in its proper finished condition. Thereby the section and full strength of the bars are preserved at the center, where it is subjected to the greatest strains, and, where if the condition of the metal is impaired as described, it is particularly injurious in promoting fracture of the bars.

As different embodiments of the herein described invention could be made without departing from the scope thereof, it is intended that all matter contained herein shall be interpreted as illustrative and not in a limiting sense. For instance in Fig. 5 I have shown my invention applied to a fish-plate of usual shape, but formed with the depression *d* both in the upper and lower surfaces, so that the plates may be reversed.

I prefer to obtain the clearance between the center of the splice-bar and the lower surface of the rail-head in the manner shown but a similar result may be accomplished by cutting or filing away the lower corners of the rail-head as shown at *c* in Fig. 6.

I claim—

1. A splice-bar for rail joints formed with a central depression on its upper edge to avoid contact with the rail ends.

Copies of this patent may be obtained for five cents each, by addressing the "Commissioner of Patents, Washington, D. C."

2. A splice-bar for rail joints having the central portion of its upper edge slightly depressed and correspondingly thickened, to prevent contact with the ends of the rails, 40 while preserving the full strength of the bar at the center.

3. A splice-bar for rail joints formed to fit snugly in the "fishing angle" of the rail, and having a depression in its upper portion adapted to be arranged adjacent the rail ends to insure clearance between the bar and the corners on the under surface of the rail ends.

4. As a new article of manufacture, a 50 splice-bar for rail-joints formed with an upper surface to engage the under side of the rail heads, and having a small depression formed in said upper surface and adapted to underlie the corners on the underside of 55 the rail ends, substantially as shown:

5. The combination in a rail joint of the two rails having their ends arranged adjacent and a splice bar bolted to said two ends to connect the two rails, said joint being 60 formed to provide a clearance between the upper surface of the splice-bar and the under side of the rail heads adjacent their ends, substantially as described and shown.

In testimony whereof I have signed my 65 name to this specification in the presence of two subscribing witnesses.

FRANKLIN E. ABBOTT.

Witnesses:

HAROLD MAGNES,
A. H. WESTON.

DISCLAIMER.

1,152,375.—*Franklin E. Abbott*, Buffalo, N. Y. SPLICE-BAR. Patent dated August 31, 1915. Disclaimer filed May 1, 1917, by the inventor and the assignee, *Lackawanna Steel Company*.

Enter this disclaimer—

“To all the claims of said patent, said claims being numbered from 1 to 5, respectively, and are as follows:

“1. A splice-bar for rail joints formed with a central depression on its upper edge to avoid contact with the rail ends.

“2. A splice-bar for rail joints having the central portion of its upper edge slightly depressed and correspondingly thickened, to prevent contact with the ends of the rails, while preserving the full strength of the bar at the center.

“3. A splice-bar for rail joints formed to fit snugly in the ‘fishing angle’ of the rail, and having a depression in its upper portion adapted to be arranged adjacent the rail ends to insure clearance between the bar and the corners on the under surface of the rail ends.

“4. As a new article of manufacture, a splice-bar for rail-joints formed with an upper surface to engage the under side of the rail heads, and having a small depression formed in said upper surface and adapted to underlie the corners on the under side of the rail ends, substantially as shown.

“5. The combination in a rail joint of the two rails having their ends arranged adjacent and a splice bar bolted to said two ends to connect the two rails, said joint being formed to provide a clearance between the upper surface of the splice-bar and the under side of the rail heads adjacent their ends, substantially as described and shown.”
